SWITCH ACTUATING DEVICE

Glenn E. Blinn, Harworth, N. J.

Application July 26, 1950, Serial No. 175,939

2 Claims. (Cl. 200—54)

1

This invention relates to devices for actuating switches of the pull type in response to the movement of a nearby object. More particularly, the invention is concerned with a novel device operable by a door being opened or closed to actuate a switch in a room or compartment, into which the door gives access. The new device is of simple, inexpensive construction with few moving parts and it may be advantageously used to control a light in a closet, operating the light switch to turn on the light, when the closet door is opened, and to turn off the light, when the closet door is closed. The new device is easy to install, requires no attention or adjustments in service, and has a long life, since none of its parts is subjected to substantial wear.

The new device comprises a base to be mounted adjacent the door as, for example, on the door frame, and a member, which may have the form of a bracket, for mounting on the door. A lever mounted on the base for swinging movement in a vertical plane has an end, which projects beyond the base and is adapted to be connected to the pull element of the switch. The swinging of the lever causes the element to be pulled to actuate the switch and is accomplished by means operatively connected to the lever and including a cam member projecting below the base in position to be engaged and moved by the bracket in its movement with the door in either direction. As the door is opened, the bracket moves the cam member to swing the lever and actuate the switch, and, when the bracket has passed by the cam member, the lever and other parts of the device are restored to their initial positions by the switch spring taking up the pull element. When the door is closed, the bracket again engages the cam member to actuate the switch and then passes by the cam member, so that the latter may be moved back to lie in the path of the bracket for actuation thereby the next time the door is opened.

For a better understanding of the invention, reference may be made to the accompanying drawing, in which:

Fig. 1 is a vertical sectional view of the device installed on the frame of a door;

Fig. 2 is a sectional view on the line 2—2 of Fig. 1;

Fig. 3 is a top plan view of part of the device;

Fig. 4 is a view in elevation of the device of Fig. 3 from the right-hand end;

Fig. 5 is a view similar to Fig. 1 but showing a modified construction;

Fig. 6 is a fragmentary view similar to Fig. 5 but showing the parts in different positions; and

Fig. 7 is a top plan view of part of the modified form of the device.

The device, as illustrated in Figs. 1—4, inclusive, comprises a base 10, which may take the form of a piece of sheet metal bent to channel form

2

and provided with lateral flanges 11, by means of which the base may be mounted adjacent to a door, as, for example, on the frame 12 of door 13. The channel extends at right angles to the door, when the latter is closed, and the forward end of the base lies near the inner side of the closed door.

A lever 14 is mounted on the base on a pivot 15, such as a rivet, which extends between the walls of the channel of the base, and the lever has a long arm 14a projecting outwardly beyond the rear end of the channel and a short arm 14b lying within the channel and formed with a slot 16. A second lever 17 lies within the channel and is pivoted at its forward end on a rivet 18 extending between the walls of the channel close to the forward end thereof. The lever 17 is provided with a cam projection 19, which normally extends through a slot in the bottom of the channel, and the rear end of the lever 17 is formed with a hook 20 entering the slot 16 in the short arm 14b of lever 14. The free end of lever 14a is adapted to be connected to the pull element, such as the chain 21, of a pull switch 22 and the connection is made in such a manner that, under ordinary conditions, the retraction of the chain by the spring of the switch moves lever 14a clockwise until the lower side of its short arm 14b engages the bottom of the channel. When lever 14a is in that position, lever 17 has been swung to the full line position shown in Fig. 1 and its cam projection 19 projects through the slot in the bottom of the base.

The device is actuated by a member 23 adapted to be attached to the rear surface of door 13 and the member is illustrated as taking the form of a bracket having an upwardly extending rear end 23a. The bracket is so mounted on the door and is of such length that, when the door is closed, the raised end 23a of the bracket lies close to the lower surface of the base beyond the downwardly projecting cam portion 19 of lever 17. When the door is opened and the bracket moves with it, the raised end 23 of the bracket engages the lower surface of the cam portion 19 of lever 17 and causes the lever to be swung clockwise, as the device is seen in Fig. 1. In the swinging of lever 17, the engagement of hook 20 on the lever with a wall of the slot 16 in lever 14 causes lever 14 to swing counterclockwise, so that the free end of the long arm 14a of lever 14 moves downwardly, pulling on chain 21 to actuate the switch and turn on the lamp 24 mounted in the switch socket. As soon as the raised end 23a of the bracket has passed by the cam projection 19 on lever 17, the switch spring retracts the chain and this moves lever 14 clockwise. In this movement of lever 14, a wall of its slot 16 engages hook 20 on lever 17 and moves the hook and lever 17 counterclockwise. The movement of the levers continues until the cam projection 19 again ex-

tends below the base in the path of the raised portion 23a of the bracket. The lamp then continues to be lighted until the door is closed. Just before complete closure of the door, the raised portion 23a of the bracket on the door engages the cam projection 19 on lever 17 and swings the lever upwardly, so that lever 14 is moved counterclockwise and the switch operated to cut off the lamp. As the lamp is turned off just before the door is completely closed, the person closing the door can tell whether the device has operated to perform its intended function.

The modified construction shown in Fig. 5 includes a base 10', which is similar to base 10 and secured to the frame 12' of door 13' in the same manner. The second form of the device includes a lever 25 pivoted at one end on a pivot 26 mounted between the walls of the channel of base 10' and the end of the lever projects outwardly beyond the base and is adapted to be connected to the pull chain 21' of the switch. The lever is operated by means actuated by a member, such as a bracket 23', attached to door 13' and such means include a cam member 27 pivoted on a rivet 28 between the walls of the channel of the base. The cam member has a cam surface 29 normally projecting through an opening in the bottom of the base and the member is provided near its rear edge with a hook 30 entering a slot 31a in one arm of a lever 31 pivoted on a rivet 32 between the walls of the channel. Lever 31 projects beyond the pivot 26 of lever 25 and is cut away at 31b, so that it may move freely despite the presence of pivot 26. To the rear of pivot 26, lever 31 is provided with a hook 33 entering an opening 34 in lever 25. At its forward end, lever 31 has a cam projection 35, which, in the normal condition of the device, projects through the same opening in the bottom of the channel as the cam member 27 and lies to the rear of the cam member.

The parts of the second form of the device are shown in Fig. 5 in the positions, which they occupy, when the door is closed and the pull chain 21' has swung lever 25 clockwise. Such movement of lever 25 has caused lever 31 to swing clockwise and cam member 27 to swing counterclockwise. The cam member 27 is in such position that its cam surface is exposed beyond the bottom of the channel and the cam projection 35 on lever 31 also projects through the opening in the channel and lies in the path of the upturned rear end of bracket 23'. When the door is opened and bracket 23' moves outwardly, the rear end of the bracket engages the rear surface of the cam projection 35 on lever 31 and causes the lever to be swung counterclockwise. This causes a similar movement of lever 25 and a clockwise movement of cam member 27. As lever 25 swings as described, it pulls on cord 21' to actuate the switch and turn on the lamp. When the rear end of the bracket has passed beyond the cam surface 29 on member 27, the switch spring retracts cord 21' and this restores the parts of the device to the positions, in which they are illustrated in Fig. 5. When the door is next closed, the rear end of bracket 23' engages the cam surface 29 on member 27 and causes the cam member to swing clockwise and levers 31 and 25 to swing counterclockwise. This results in the chain 21' being pulled to actuate the switch to put out the lamp and, when the end of bracket 23' has passed beyond cam surface 29, the parts assume their normal positions shown in Fig. 5.

In both constructions described, it will be noted that the arm of lever 14 or 25 connected to the pull chain of the switch is longer than the arm, which is operated by the action of the bracket on the door. A small movement of lever 17 or of cam member 27 and lever 31, accordingly, produces a relatively larger movement of the free end of lever 14 or 25, such movement being sufficient to pull the cord to the extent necessary to operate the switch. The construction shown in Fig. 5 has one more moving part than that shown in Fig. 1 but is somewhat easier to operate because of the position of pivots 28, 32 in relation to the path of travel of the rear end of the bracket.

I claim:

1. A device for operating a pull switch, which comprises a base adapted to be mounted adjacent a door, a lever pivoted at one end on the base for movement in a vertical plane and having an arm projecting beyond the base in a direction away from the door, the free end of the arm being adapted to be connected to the pull element of the switch, and means mounted on the base and operable by the member moving with the door to swing the lever to pull the element to actuate the switch, said means including a cam member pivoted on the base and having a portion normally projecting beyond the base into the path of travel of the member on the door, as the door approaches the base, and a second lever pivoted on the base to swing in a vertical plane and having one end continuously connected to the first lever and its other end continuously connected to the cam member, the second lever having a cam portion normally projecting beyond the base into the path of travel of the member on the door in the initial movement of the member, as the door is moved away from the base.

2. A device for operating a pull switch, which comprises a base adapted to be mounted adjacent a door, a lever pivoted at one end on the base for movement in a vertical plane and having an arm projecting beyond the base in a direction away from the door, the free end of the arm being adapted to be connected to the pull element of the switch, a second lever pivoted on the base and having one end continuously connected to the first lever, the second lever having a cam portion normally projecting below the base into the path of travel of the member on the door, and a cam lever pivoted on the base and continuously connected to the other end of the second lever, the cam lever having a cam portion normally projecting below the base into the path of travel of the member on the door, the cam portion of the cam lever lying in position to be engaged first by the member on the door, as the door is approaching the base.
